UNITED STATES PATENT OFFICE

2,416,707

IMPRINTING MACHINE

Albert W. Metzner, Dayton, Ohio, assignor to The Standard Register Company, Dayton, Ohio, a corporation of Ohio

Application July 20, 1942, Serial No. 451,542

5 Claims. (Cl. 101—93)

1

This invention pertains to writing and imprinting apparatus, including tabulating, billing and recording machines, and more particularly to imprinting means for automatically producing vertical line rulings in optionally selected positions upon inscribed record sheets and strips coincidental with the inscribing operation.

It is customary commercial practice to employ preprinted record forms which are ruled horizontally and vertically to define writing positions in vertical columns wherein to enter inscribed indicia.

While the line spacings are arbitrarily determined by the record material feeding devices of the recording apparatus, with which the horizontal rulings must necessarily agree, the relative position and widths of the vertical columns defined by vertical rulings may vary from time to time in accordance with the character, extent and arrangement of tabulations to be inscribed. Consequently, for conditions wherein it is necessary to frequently change the arrangement of tabulations and to change the size and relation of vertical columns, such standardized record material is undesirable and record material wherein the vertical columnar rulings may be optionally disposed is much more economical and convenient. However, hand ruling of the forms either before or after inscription is impractical and uneconomical.

Likewise, it is impractical and uneconomical to have small quantities of forms of particular arrangement preprinted. The necessary composition and "make ready" for a small quantity of forms of particular style is equally as great for a small quantity of printed forms as it would be for a large supply thereof. The present invention enables the preprinted use of stock forms of universal character for a wide variety of different optional arrangements of columns.

In the present development there is contemplated a series of identical imprinting type elements which may be mounted in an attachment or supplementary unit for a recording apparatus as herein illustrated, or which are preferably incorporated in the recording apparatus at the time of manufacture. These identical type elements are positioned to imprint short, vertical lines approximately one line space in length intermediate the usual letter and figure characters. The succeeding impressions of any one of such rule type elements in successive line space positions registers with and joins end to end or overlaps the preceding and succeeding vertical impressions to conjointly produce continuous ver-

2

tical lines. Such vertical rule impressions are produced simultaneously with adjacent letter or figure character impressions, but not with every such impression.

5 Means is incorporated in the mechanism to optionally enable simultaneous imprinting of characters and vertical rule impressions, or character impressions without accompanying vertical rule imprints, or such vertical rule imprints without accompanying character impressions.

10 By disabling or rendering ineffectual certain selected rule type elements, disposition of vertical rule lines are enabled at any optionally determined spaced intervals. As a result it is possible to inscribe upon a record sheet one or a plurality of columns of numbers of any size, containing few or many digits, and continue the vertical rule defining the column while inscribing the last digit of each number, or such vertical rule imprints 15 may be effected intermediate any adjacent digits of the numbers as between those representing dollars and cents, or if desired between all the columns of digits, thus effecting cross section ruling in the squares of which the letter figure 20 characters appear. The apparatus is thus of wide flexibility, and enables the production of a great variety of inscribed forms, without the necessity of specially prepared stationery. Stock stationery having desired imprinted headings and with 25 or without horizontal line space rulings may be employed for all different forms, and styles of tabulations, the columnar rulings for which are optional and which are automatically produced during inscription of such forms without additional operation.

30 The object of the invention is to improve the construction as well as the means and mode of operation of writing and imprinting apparatus by incorporating optionally selective vertical 35 ruling devices therein, which may be economically manufactured and incorporated, whereby such apparatus will be more efficient and useful, automatic in operation, uniform in action, having relatively few additional parts, and be unlikely to 40 get out of repair.

45 A further object of the invention is to provide operationally selective vertical ruling devices in a recording apparatus which are automatically operable coincidentally with the actuation of the 50 recording apparatus.

55 A further object of the invention is to improve tabulating and analogous writing and imprinting apparatus by incorporating therein an additional series of type elements for imprinting successive segments of optionally positioned vertical lines.

A further object of the invention is to provide in a combined imprinting and line ruling mechanism control means by which character imprinting and line rule imprinting can optionally be performed simultaneously or either independently of the other.

A further object of the invention is to provide a recording and line ruling apparatus having the advantageous structural features and inherent meritorious characteristics and the mode of operation herein set forth.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the drawings, wherein is shown the preferred but obviously not necessarily the only form of embodiment of the invention,

Fig. 1 is a vertical sectional view of a conventional tabulating machine with which the line ruling devices forming the subject matter hereof have been incorporated, and showing the latter adjusted to effect imprinting of the vertical rule only.

Fig. 2 is a top plan view of the platen roll and imprinting type bars and the line rule type elements.

Fig. 3 is a detail view of the imprinting devices adjusted for simultaneous character and line rule imprinting.

Fig. 4 is a detail plan view on line 4—4 of Fig. 3.

Fig. 5 is a side elevation similar to Fig. 3, showing the line rule imprinting devices retracted to inoperative position, permitting character imprinting only.

Fig. 6 is a detail plan view of the parts in retracted position as in Fig. 5.

Fig. 7 is a detail front elevation in the plane 7—7 of Fig. 3.

Fig. 8 is a similar detail elevation in the plane 8—8 of Fig. 5.

Fig. 9 is a perspective view of a packet of stock stationery prior to inscription.

Fig. 10 is a fragmentary view of a portion of continuous form stationery after being inscribed and vertical line ruled.

Fig. 11 is a perspective view of the line rule elements in disassembled relation.

Fig. 12 is a detail view of adjusting means for the line type arms.

Fig. 13 is a vertical sectional view illustrating a modification of the line ruling devices.

Like parts are indicated by similar characters throughout the several views.

For illustrative purposes, but with no intent to unduly limit the scope or application of the invention, it is herein illustrated and described as applied to a conventional type of International Business Machine (I. B. M.) tabulator, which is shown equipped with a "Registrar" pin type platen roll for feeding marginally punched record material. It is to be understood, however, that the invention is not limited to either the particular tabulator construction, nor to the use of marginally punched stationery, although the latter is highly desirable for purpose of maintaining registry and alignment, especially in production of closely inscribed tabulated forms. In proper size and modified form the invention is applicable to tabulators of other manufacture and to

other forms and styles of writing and imprinting apparatus, and is to be so understood.

The tabulating and character imprinting mechanism herein shown and described forms no part, per se, of the present invention, except as the line ruling devices are claimed in combination therewith, and hence the tabulating mechanism is herein referred to but briefly.

Referring to Fig. 1, the group of mechanism A at the right is a part of the conventional tabulator mechanism including the platen roller 1 to which the record material or stationery 2 is advanced over the paper guide 3, and about which it is advanced through step by step movement, incident to the line space operation of the platen roll 1, past a writing position 4 and thence discharged from the machine at 5. The stationery as it enters the machine over the guide 3 may be merely blank sheets or strips. It may comprise "cut forms" or individual sheets of record material. However, it preferably comprises continuous strips of series connected detachable forms divisible upon transverse longitudinally spaced weakened lines into individual sheets, each of which forms has a preprinted heading and is horizontally ruled to agree with the line spacing advancement thereof by the machine. If a pin type feeding device is employed, the material is marginally or otherwise punched as at 6 for progressive engagement of feeding pins. Standard line spacings are either one-sixth or one-third inches. Such stationery is initially devoid of vertical lines or columnar rulings. However, as the stationery leaves the machine at 5 it contains both character or indicia imprints and selectively spaced vertical rulings which define the columns in which the characters are imprinted.

The group of mechanism B at the left of Fig. 1 is also a part of the conventional tabulating apparatus and is enclosed in a portion 7 of the tabulating machine cabinet. Intermediate the groups A and B of mechanism is a vertically reciprocatory type carrier 8 bearing a large number of alphabetical and numerical reciprocatory spring retracted type elements 9. There is a succession of reciprocatory type carriers 8, one for each character to be imprinted, throughout the entire length of an inscribed line, which are arranged side by side opposite the platen roll. The standard lineal type spacings are five thirty-second of an inch. It will be understood that line space dimensions and lineal type spacing are in no way material to the present invention.

Although the reciprocatory type carriers 8 are uniformly spaced closely together, nevertheless in such machines as now constructed and those now in use, there is sufficient clearance between adjacent carriers to enable a thin, flat movable type element, the terminal face of which defines a short, vertical line or bar, to be operated intermediate the type carriers.

A tabulator of the character illustrated is power driven and automatically controlled by punched cards or tape to variously adjust different type carriers 8 of the plurality to present predetermined type elements in aligned sequence opposite the imprinting position 4 of the platen roll.

A series of spring actuated pivoted hammers 10 upon release forcibly drive the positioned type members against the record material disposed about the platen roll. The type hammers 10 are normally held in retracted position by a series of swinging detent arms 11, of which there is one for each hammer. The detent arms are detach-

ably connected by hook arms 12 with a swinging bar 13 carried by oscillatory arms 14. The movement of unselected type carriers into non-printing position trips a short lever 15 which in turn oscillates the hook arm 12 corresponding to the particular type carrier to elevate it from engagement with the swinging frame bar 13. In the cycle of operation of the tabulator, the arms 14 are oscillated in proper sequence with other movements to retract those hook arms 12 which have not been disengaged, and so retract the detents 11 of the corresponding type hammers 10, which thereupon impinge upon the positioned type members under influence of actuating springs 16, while the hammers pertaining to the carriers of unused type remain in retracted positions. As an alternative means of maintaining the hammers 10 pertaining to unused type carriers ineffective, there is shown a spring detent finger 17 engageable in a notch 18 in the top of the corresponding hammer under influence of a manually adjustable lever 19. Such is the conventional operation of the tabulating mechanism, and, per se, forms no part of the present invention, except in combination with the line rule imprinting devices. The present line rule mechanism is illustrated as an attachment mounted on top of the tabulator cabinet 7. It may, however, comprise mechanism incorporated as a component part of the tabulator or writing apparatus at the time of its manufacture.

Mounted in brackets 20 on the machine cabinet 7 is a shaft 21 disposed in parallel relation with the platen roll 1. Journaled on the shaft 21 is a series of relatively spaced oscillatory arms 22 separated by spacer collars 23. There is one arm 22 for each type carrier 8. Each arm 22 is formed with an integral stop finger 24 engageable with a bar 25 interconnecting the mounting brackets 20 when the arm is in its advanced or operative position, as shown in Figs. 1 and 3.

Pivotally supported on a stud 26 carried by each of the arms 22 is an oscillatory line rule type element 27 for swinging movement against the positioned record material. Each rule type member 27 is yieldingly held in its retracted position by a spring finger 28 which bears upon a flat terminal of the type element above its pivotal stud 26. Slidingly mounted on the swinging type member 27 for independent reciprocating movement relative thereto but for unison swinging motion is a coupler slide 29. The coupler slide has therein a dumb-bell shaped slot 30 through the upper enlarged portion of which the pivotal stud 26 carried by the arm 22 extends. Journaled in the oscillatory line type member 27 and extending through the dumb-bell slot 30 below the pivotal stud 26 is a flattened rock stud 31, to which is attached a finger lever 32. When the finger lever 32 is in its depressed position, to which it will fall by gravity, the flattened stud 31 is transversely disposed within the lower enlargement of the slot as in Fig. 3 to lock the coupler slide 29 in its elevated position relative to the line rule type 27. When however, the flattened stud is turned into vertical position by elevation of the finger lever 32, the slide 29 may be depressed until the lower end of the slide 29 will substantially agree with the lower rear extremity of the swinging line rule type member, as shown in Fig. 1 and also in Fig. 5. The coupler slide is laterally offset at its lower end, whereby its extremity will extend into the plane of the line rule type member 27 and when depressed into the path of the corresponding type hammer 10. The lower

end of the slide 29 thus transmits motion and pressure of the type hammer 10 to the swinging rule type member 27 and swings with the type member as the latter is forced against the record material. Figs. 1, 3 and 5 of the drawings illustrate alternative adjustments of the line rule parts to produce respectively, a line rule imprint only, line rule and character type imprints simultaneously, or a character imprint only.

In Fig. 1 the lower end of the coupler slide 29 being interposed between the line rule member 27 and the hammer 10 receives and transmits the impact of the latter to the line rule member 27, which is thrust against the record material overlying the platen 1, to produce a vertical line impression. The combined dimensions of the coupler slide 29 and the line rule imprinting member 27 is sufficient to hold the hammer 10 out of contact engagement with a positioned character type 9. In Fig. 3 the coupler slide 29 is shown elevated out of the path to the impact hammer 10 which is sufficiently wide to simultaneously engage both the line rule element 27 and a character type 9 positioned in imprinting position, to drive both members against the record material and produce both a character and a vertical line imprint. In Fig. 5 the entire line rule imprinting assembly is shown retracted to inoperative relation so that the advancing hammer 10 operatively engages only a character type to produce a character imprint only.

The coupler slide 29 is formed with a finger hold or extension 33 at its upper end, and its rear margin is formed with an arcuate wing 34 contoured to agree with the periphery of the spacer collar 23. When a line rule impression is to be produced simultaneously with a letter or figure character, the finger lever 32 is elevated to vertically align the flattened stud and the coupler slide 29 may be manually elevated from its Fig. 1 position to that of Fig. 3 which withdraws it from the path of the hammer 10, and allows the latter to strike against both the swinging line type member 27 and the reciprocatory letter or figure type member 9. If it be desired to imprint a vertical line impression unaccompanied by a character impression, upon turning the flattener stud 31 into alignment with the neck of the dumb-bell slot the coupler slide may be depressed to the Fig. 1 position, where, as before mentioned, it receives the impact of the hammer 10 before the latter can reach a character type element 9 and prevents such contact.

When it is desired to omit entirely the line rule and effect a letter or figure type impression only, the line rule member 27 is bodily displaced to inoperative position shown in Fig. 5. To do so, the coupler slide 29 is manually lifted until the flattened stud 31 enters the enlarged lower end of the slot 30, whereupon the finger lever 32 falls by gravity and turns the flattened stud transversely of the slot, thereby locking the slide 29 in its retracted position, as is shown in Fig. 3. The supporting arm 22 is then oscillated to a substantially upright position, as is shown in Fig. 5, and the finger lever 32 being elevated to align the flattened stud with the slot 30, the coupler slide 29 is manually depressed to a position wherein the arcuate wing portion 34 engages about the spacer collar 23 to temporarily lock the line rule parts in inoperative position, as in Fig. 5.

The line rule assembly heretofore described does not necessitate any change in the construction arrangement of a conventional tabulator

apparatus, nor interfere with its operation. By taking advantage of the relative spacing of the type carriers, it is adapted to be installed on existing machines in the form illustrated in the drawings, although it may be otherwise incorporated in the machine at the time of its manufacture. The positions and relative spacing of the down rules are predetermined, and the corresponding line rule imprinting elements are selectively arranged by individual manual adjustment of the coupler slides 29 into and out of operative position, or by retracting undesired rule imprint elements to the inoperative position of Fig. 5. When once set, no further attention need be given to the present line rule mechanism until it becomes necessary to reset it for operating upon a series of differently ruled record sheets.

In lieu of imprinting successive short line rules in end to end sequence to form continuous vertical line rules, a scribe or point 35 may be provided on the extremity of the member 27 for continuous engagement with the record material, as shown in Fig. 13. The marking member 27 in such event is spring urged into engagement with the record material by a spring 36. The marking members 27 being positioned intermediate the type carriers 8, as before described, and their scribe points 35 being maintained in engagement with the record material by the springs 36, continuous vertical lines or rules will be impressed thereon as the platen roll by its rotation advances the record material past the recording position and the scribe or marking point 35. The marking members 27 are provided with finger levers 37 by which individual members may be manually retracted when not desired for use.

Detents 38 serve to releasably retain the undesired and unused line ruling devices in their retracted positions against the tension of their pressure applying springs. In such modified construction the optionally selected ruling members, once released from the detent 37 remain in constant operative engagement with the record material and continue to impress line rulings thereon, until again manually retracted. The operative pressure of the springs 36 is adjusted to sufficiently impress a line mark through the ink ribbon and transfer material if used, but not to afford such pressure as will interfere with the feeding of the ink ribbon or advancement of the record material.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A recording apparatus of the type wherein a

plurality of predetermined character imprinting elements are automatically aligned in printing position for engagement with record material progressively advanced past an imprinting position wherein it receives successive lineal impressions of aligned imprinting elements under impact influence of a series of operating members, one for each character imprinting element, including a plurality of optionally selective vertical line imprinting elements arranged in alternating relation with the character imprinting elements, an adjustable supporting means for the line printing elements by which the said line printing elements may be individually bodily shifted into and out of imprinting position in which they are engageable by an impact character imprinting element operating member simultaneously with its impact engagement with an imprinting element, for optionally effecting simultaneous character and line imprinting operations or character imprinting operations only, coupler members individually bodily movable into and out of positions in the paths of the impact operating members for transmitting the impact thereof to corresponding line imprinting elements independently of the corresponding character imprinting elements to which said impact operating members pertain to effect line imprinting operations only.

2. A recording apparatus of the type wherein a plurality of predetermined character imprinting elements are automatically aligned in printing position for engagement with record material progressively advanced past an imprinting position wherein it receives successive lineal impressions of aligned imprinting elements under influence of individual impact operating devices for the character imprinting elements, including a plurality of vertical line imprinting elements operative between different adjacent character imprinting elements, the respective character imprinting element operating devices being common to an adjacent line imprinting element for effecting simultaneous imprinting engagement of the character imprinting elements and certain optionally selected vertical line imprinting elements and selective means for rendering the common operating devices ineffective to operate a character imprinting element or a line imprinting element at will.

3. A recording apparatus, wherein a succession of characters are imprinted in lineal series upon a record sheet, including a series of line imprinting elements operative to impress vertical line imprints upon the record sheet intermediate selected character imprints, actuating means therefor, a supporting shaft, a series of independently adjustable oscillatory arms upon the shaft to which the line imprinting elements are pivoted for independently swinging motion, by adjustment of which the line imprinting elements are shiftable into and out of line printing position, slide members associated with the line printing elements and adjustable relative thereto into and out of the path of the line imprinting element operating means for optionally transmitting operative action of the actuating means to the line printing elements or alternately permitting direct engagement of the actuating means therewith.

4. A line imprinting mechanism for a recording apparatus having a succession of character imprinting elements, including an oscillatory supporting arm, an oscillatory line imprinting element carried by the oscillatory arm and adjustable into and out of operative position by adjustment of the arm, a slide member also carried by the oscillatory supporting arm and adjustable in-

dependently of the line imprinting member into alternate positions relative thereto, and means for temporarily engaging the slide in its alternate positions of adjustment to accordingly effect operation of the line imprinting element independently of or simultaneously with operation of a character imprinting element.

5. A line imprinting mechanism for a recording apparatus, wherein a plurality of character imprinting elements are presented in aligned relation and actuated into imprinting engagement with a record material by relatively movable pressure applying means engageable with the character imprinting elements, including a plurality of independently operable line imprinting element 15 operative intermediate adjacent character imprinting elements under influence of the said pressure applying means to imprint vertical line segments upon the record material intermediate succeeding character imprints, means for independently adjusting the line imprinting elements into and out of imprinting position, and a control member adjustable into and out of relation with

said pressure applying means to temporarily protect a selected character imprinting element from operative engagement of the pressure applying means therewith while said pressure applying means exerts its influence upon an adjacent line printing element.

ALBERT W. METZNER.
